UNITED STATES PATENT OFFICE.

HENRY A. HANSEN, OF NEW YORK, N. Y., ASSIGNOR OF ONE-HALF TO
PAUL OLSEN, OF NEW YORK, N. Y.

WATER-VEHICLE.

SPECIFICATION forming part of Letters Patent No. 738,436, dated September 8, 1903.

Application filed October 28, 1902. Serial No. 129,080. (No model.)

To all whom it may concern:

Be it known that I, HENRY A. HANSEN, a citizen of the United States, residing at New York, in the county of New York and State 5 of New York, have invented certain new and useful Improvements in Water-Vehicles, of which the following is a specification, such as will enable those skilled in the art to which it appertains to make and use the same.

10 The object of this invention is to provide an improved water-vehicle which may be propelled by the foot or by a suitable motor and which is simple in construction and operation and by means of which great speed 15 may be obtained; and with this and other objects in view the invention consists in a vehicle of the class specified constructed as hereinafter described and claimed.

In the drawings forming part of this specification, in which the separate parts of my improvement are designated by suitable reference characters in each of the views, Figure 1 is a side view of my improved water-vehicle, and Fig. 2 a plan view thereof.

25 In the practice of my invention I provide a strong main frame composed of steel tubes, bamboo rods, or any other suitable material, and this frame comprises an upright front member a , a horizontal top member a^2 , and 30 a downwardly and backwardly directed rear member a^3 , and suspended centrally of this frame in the form of construction shown is a crank-hanger b , said crank-hanger being suspended by means of a rod b^2 , which extends 35 forwardly and upwardly, a central rod b^3 , which extends upwardly and backwardly, and a rear rod b^4 , which extends backwardly and downwardly, and the rods b^2 , b^3 , and b^4 are connected with couplings b^5 , b^6 , and b^7 , 40 with which the rods or members a , a^2 , and a^3 are also connected, and said rods b^2 , b^3 , and b^4 constitute a part of the main frame.

Mounted in the lower part of the end portions of the main frame is a shaft c , the front 45 end of which is provided with a beveled gear-wheel c^2 , and supported adjacent to the beveled gear-wheel c^2 by means of a bracket c^3 or in any desired manner is a sprocket-wheel c^4 , provided with a bevel-gear c^5 . In the form 50 of construction shown the crank-hanger b is provided with a pedal-shaft d , having pedal-

cranks d^2 , this construction corresponding with and being similar to the corresponding parts of a bicycle, and the pedal-shaft d^2 is provided with a sprocket-wheel d^3 , which is 55 geared in connection with the wheel c^4 by an ordinary drive-chain d^4 . The shaft c passes centrally through an elongated propeller-float e , which is pointed or conical at both ends and which may be made of any desired material, but which in practice is preferably made of sheet metal treated so that it will not be injuriously affected by water, and the propeller-float e is provided with a spirally-arranged propeller-blade e^2 , which extends 60 from one end thereof to the other.

Mounted over the front end of the main frame is an ordinary handle-bar f , similar to the handle-bar of a bicycle and provided with the usual handle f^2 , and at the front of 70 the main frame is a forwardly-directed bracket or support comprising top and bottom members f^3 and f^4 and an upright tubular member f^5 , through which is passed a rod g , the upper end of which is provided with a cross-bar g^2 , which is connected by means of links g^3 with the opposite ends of the handle-bar f , and the lower end of the rod g is provided with a forwardly-directed fork g^4 and a backwardly-directed fork g^5 , in which is held a 75 steering-float h . The steering-float h is similar in form to the propeller-float e , being cylindrical in cross-section and pointed at both ends, and this float may be made in the same manner as the propeller-float e , and is provided at the bottom thereof with a longitudinally-arranged fin-keel h^2 .

The main frame is provided with a seat i , similar to a bicycle-seat, and the operation of the construction herein shown and described will be readily understood from the foregoing description, taken in connection with the accompanying drawings. In practice the vehicle is placed in the water in the manner of an ordinary boat, and the operator sits on the seat i and operates the pedals d^2 and the drive-chain d^4 , and by means of the gear-wheels c^2 and c^4 the propeller-float e is rapidly revolved and the vehicle is propelled, as will be readily understood, by means 95 of the spiral propeller e^2 . The steering-float h may be manipulated by the handle-bar f 100

so as to guide the vehicle in any desired direction, and it may also be manipulated so as to aid in holding the vehicle in an upright position.

5 My invention is not limited to the exact form and construction herein shown and described, and if necessary for the convenient operation of the vehicle the main frame may be provided with laterally-directed extensions having supplemental floats, which will rest on or in the water and hold the vehicle in an upright position at all times.

It will be understood that in practice the propeller-float *e* is half or more than half 15 submerged at all times, as indicated by the dotted line *j*, and this is also true of the steering-float *h*, and the said floats while being preferably of the form herein shown and described may be made in any desired manner 20 and of any preferred material.

Although I have shown and described means for operating the propeller-float by the feet of an operator, my invention is not limited to this form of construction, and I may 25 employ, if desired, a motor of any desired form or construction which would be supported in the main frame and geared in connection with the shaft *c* of the propeller-float.

Having fully described my invention, what 30 I claim as new, and desire to secure by Letters Patent, is—

1. A water-vehicle comprising a main frame, a propeller-float mounted longitudinally in the bottom thereof and provided with 35 a shaft, said propeller-float being circular in cross-section and pointed at the front end, and provided with a spirally-arranged propeller, devices for turning the propeller-float, a support at the front of the main frame, a rod 40 passing vertically therethrough a steering-float connected with the lower end of said

rod, a handle-bar connected with the main frame and devices whereby said handle-bar is put in operative connection with the steering-float, substantially as shown and de- 45 scribed.

2. A water-vehicle, comprising an upright main frame, a seat mounted thereon, a pedal-shaft mounted therein, a propeller-float 50 being circular in cross-section and pointed at both ends, and provided at the front end with a gear-wheel, a sprocket-wheel operating in connection with said gear-wheel, a sprocket-wheel on the pedal-shaft geared in connection with the first-named sprocket-wheel, and means for steering the vehicle, substantially as shown and described.

3. A water-vehicle, comprising an upright main frame, a seat mounted thereon, a pedal-shaft mounted therein, a propeller-float 60 being circular in cross-section and pointed at both ends, and provided at the front end with a gear-wheel, a sprocket-wheel operating in 65 connection with said gear-wheel, a sprocket-wheel on the pedal-shaft geared in connection with the first-named sprocket-wheel, and means for steering the vehicle, consisting of a steering-float supported in front of the propeller-float and means for operating said steering-float, substantially as shown and described.

In testimony that I claim the foregoing as my invention I have signed my name, in presence of the subscribing witnesses, this 75 day of October, 1902.

HENRY A. HANSEN.
